PLAYGROUND SPRINKLER

Anita Margrill, 151 W. 13th St., New York, N.Y. 10011

Filed Mar. 19, 1971, Ser. No. 126,386

Term of patent 14 years

Int. Cl. D23—01

U.S. Cl. D23—6

FIG. 1 is a front perspective view of a playground sprinkler embodying my new design;

FIG. 2 is a right side elevational view thereof;

FIG. 3 is a left side elevational view thereof;

FIG. 4 is a top plan view thereof; and,

FIG. 5 is a bottom plan view thereof.

I claim:

The ornamental design for a playground sprinkler, as shown.
